(57) **CLAIM**

The ornamental design for a pedestal surface, as shown and described.

DESCRIPTION

FIG. 1 is an elevated right rear perspective view of a pedestal surface showing our new design, the broken line showing being for illustrative purposes only, and forms no part of the claimed design.

FIG. 2 is a left front perspective view of the pedestal surface design of FIG. 1.

FIG. 3 is a rear view of the pedestal surface design of FIG. 1.

FIG. 4 is a right side view of the pedestal surface design of FIG. 1.

FIG. 5 is a left side view of the pedestal surface design of FIG. 1; and,

FIG. 6 is a plan view of the pedestal surface design of FIG. 1.
